CLAIM

The ornamental design for a baby chair with debris catcher as shown and described.

DESCRIPTION

FIG. 1 is a front perspective view of the baby chair with debris catcher showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is the claimed design shown in FIG. 1 secured to a counter or table.

Portions of the drawings shown in broken lines form no part of the claimed design.

1 Claim, 5 Drawing Sheets
